UNITED STATES PATENT OFFICE.

GEORGE BYRON LEGG, OF DETROIT, MICHIGAN.

LAUNDRY-TRAY SUPPLY.

1,261,248.

Specification of Letters Patent. Patented Apr. 2, 1918.

Application filed October 11, 1916, Serial No. 125,003. Renewed August 27, 1917. Serial No. 188,480.

To all whom it may concern:

Be it known that I, GEORGE BYRON LEGG, a citizen of the United States, and a resident of Detroit, in the county of Wayne and State 5 of Michigan, have invented a certain new and useful Improvement in Laundry-Tray Supplies, of which the following is a specification.

My present invention relates to laundry 10 tray supplies, that is, conducting means for hot and cold water particularly well adapted for use in operative relation to laundry trays and for connecting with the usual leads from the hot and cold water systems.

15 It is now common practice to instal laundry trays with the supply pipes strapped to a board disposed above and at the rear of the trays, which is unsatisfactory since the wood rots and is rated unsanitary. When 20 it is desired to set the tray at a substantial distance, say fifteen or eighteen inches, or more, from the wall, so as to position the trays in a section of the laundry which is well lighted, the installation is rendered expensive because of the numerous T's, elbows, 25 and pipe sections required, in addition to the time and labor incidental to installation.

One of the principal objects of my invention is therefore to provide supplies for 30 laundry trays or other plumbing fixtures which require no wooden supports and which obviate the necessity of a number of pipe fittings and sections adjacent the trays, reducing the initial cost and time and labor 35 required for installation.

Laundry trays as now manufactured provide ways whereby the inlets or taps extend through the rear walls thereof, but which reduce the capacity of the trays inasmuch as it 40 is objectionable to run the water with its surface above the egress openings of the taps. A board or strip of material is usually placed above supply pipes arranged in this manner to give finish to the installation, but the 45 boards are also apt to rot and become unsanitary. Therefore, another object of my invention is to provide supplies of the character described which may be mounted above or upon the rear walls of the trays so that 50 the taps are above the upper margins of the trays, and render the job neat in appearance without the use of concealing strips or housings.

55 Other objects of my invention will appear in the following detailed description, taken in connection with the accompanying draw-

ing, forming a part of this specification, and in which drawing:—

Figure 1 is a vertical transverse sectional view through a laundry tray, showing a 60 supply embodying my invention as applied thereto.

Fig. 2 is a front elevation of one section of the supply.

Fig. 3 is a plan view of the two sections of 65 the supply in operative relation one to the other.

Fig. 4 is a similar view of the co-acting section to that shown in Fig. 2.

Fig. 5 is an enlarged sectional view on 70 the line 5—5 of Fig. 3, showing a tap in operative relation to one of the conduits.

Fig. 6 is an enlarged sectional view on the line 6—6 of Fig. 3, with tap in place.

Fig. 7 is an enlarged sectional view taken 75 on the line 7—7 of Fig. 3, showing one of the intermediate projections and a tap secured thereto.

In the drawing, where similar characters refer to similar parts throughout the several 80 views, A designates a laundry tray including the usual rear wall B; C a hot water supply pipe; D a cold water supply pipe; E a fixture supply embodying my invention and including a conduit F for hot water, and a conduit 85 G for cold water; H a hot water inlet tap; and, J a cold water inlet tap.

Referring first to the conduit F, it is elongated to extend longitudinally of the tray A, and is preferably polygonal in cross section as clearly shown in Fig. 5 of the drawing. Laterally extending projections 8, provided with tap openings 9, are preferably formed integral with the main body portion of the conduit, these extensions being in 95 spaced relation. One end portion of the conduit is closed as at 10, and it is preferred to provide at the other end portion an ingress opening 11 for connection with the hot water supply pipe C.

100 Referring now to the conduit G, it is also elongated so as to extend longitudinally of the tray A, and is preferably formed polygonal in cross section and of substantially rectangular outline, providing two legs 12 and 105 13, the leg 12 overlying the conduit F and the leg 13 fronting the same. Ways 14 are provided in the leg 13 for the reception of the projections 8 of the conduit F, or so as to expose the tap openings 9 of the conduit 110 F to the front of the supply. The conduit G is also provided with tap openings 15 in

leg 13, open laterally of the supply. The conduit G may be closed at one end, as indicated at 16, and at its other end may be provided with an ingress 17 for connection with 5 the cold water supply lead D.

It is preferred to so arrange the tap openings 15 of conduit G with respect to the ways 14 that when the conduits are in assembled relation one to the other, the tap 10 openings 15 of conduit G alternate with the tap openings 9 of conduit F. By this arrangement, when the supply is disposed in operative relation to the laundry tray, the egress for the hot water will have the same 15 relative position with respect to one section of the laundry tray as the hot water egress is disposed with respect to the other section of the laundry tray.

In disposing the supply in operative relation to the plumbing fixture, as in the example shown, it may rest upon the rear wall B or may be disposed thereabove. The conduit G conceals or protects the conduit F which latter is preferably connected with 20 the supply pipe C for hot water, and in this way, injury as by burning, is prevented if the hot water is of high degree of temperature. The taps H and J are turned into their respective tap openings and it is to be 25 observed that all of the taps are in substantially the same plane. The upper portion of the conduit G provides a ledge or shelf adjacent the laundry tray, giving finish to the same, and if desired, the supply may be 30 placed to the rear of the tray, bringing the top face of the supply adjacent the top margin of the rear wall B.

While I have herein shown the supply as disposed into operative relation to a laundry tray, it is to be understood that the invention is applicable to other types of plumbing fixtures, which are elongated and provided with a plurality of compartments to each receive hot and cold water.

45 Changes in details may be made without departing from the spirit or scope of my invention; but,

I claim:—

50 1. A plumbing fixture supply comprising in combination, an elongated conduit having forwardly extending projections provided with tap openings, and a second elongated conduit provided with front tap openings and formed to overlie the top and front of said first conduit, the second conduit having 55 ways to receive the said projections of said first conduit whereby to expose all of the tap openings at the front of the supply.

60 2. As an article of manufacture, a plumbing fixture supply comprising a pair of independent interfitting hollow castings having supply pipe receiving openings and formed to inclose one of the castings within

the other, the inner casting having lateral 65 projections and the outer casting having ways to receive the projections, the outer casting and said projections having alternately arranged tap-receiving openings therein.

3. A plumbing fixture supply comprising 70 in combination, an elongated conduit including laterally extending projections provided with tap openings, and a second elongated conduit provided with lateral tap openings and formed to overlie the top and front of said first conduit, and provided with ways to receive the said projections of said first conduit exposing all of the tap 75 openings at the front of the supply, the tap openings and ways of said second conduit 80 alternating to hold the conduit in interfitting relation.

4. A plumbing fixture supply comprising 85 in combination, an elongated conduit including laterally extending projections provided with tap openings, said conduit closed at one end and provided with an ingress opening at its other end, and a second elongated conduit provided with lateral tap openings and formed to engage the front of said first 90 conduit to house the same and having ways to receive the said projections of said conduit, whereby to expose all of the tap 95 openings at the front of the supply.

5. A plumbing fixture supply comprising 95 in combination, an elongated conduit having forwardly extending projections provided with tap openings, said conduit being closed at one end and provided with an ingress opening at its other end, and a second elongated conduit closed at one end and provided with an ingress opening at its other end and having lateral tap openings, said second conduit formed to overlie the top and front 100 of said first conduit and having ways to receive the said projections of said first conduit, whereby to expose all of the tap 105 openings at the front of the supply.

6. The combination with a plumbing fixture including a water-receiving receptacle 110 adapted to be installed adjacent to a wall, of a supply including a hot water conduit adapted to rest on the upper edge of said fixture and against the wall and having forwardly extending tap-receiving projections 115 overhanging the receptacle, and a cold-water conduit of angular form fitting against the exposed top and front side of the hot-water conduit to house the latter and to provide a ledge between the fixture and the 120 wall, and having in its front portion ways to receive said projections of said first conduit and tap receiving openings in line with the openings of said projections.

GEORGE BYRON LEGG.
